FACE POWDER CONTAINER

Filed April 19, 1927

INVENTOR.

GERTRUDE B. DENNIS
BY

R. H. Hallmark
ATTORNEY.

UNITED STATES PATENT OFFICE.

GERTRUDE B. DENNIS, OF STEAMBOAT SPRINGS, COLORADO.

FACE-POWDER CONTAINER.

Application filed April 19, 1927. Serial No. 184,911.

This invention relates to containers for face powder more particularly of the type adapted for use on a dressing stand or table. In containers of this type, at present on the market, no separate provision is made for holding the powder puff and it must either be thrown in with the powder in the container, where it accumulates an excess of powder, or it must be laid aside.

10 The principal object of the present invention is to provide simple and efficient means in a face powder container of this type for holding the powder puff within the container and out of contact with the face powder therein.

Other objects and advantages reside in the detail construction of the invention, which is designed for economy, simplicity and efficiency. These will become more apparent 20 from the following description.

In the following detailed description of the invention reference is had to the accompanying drawing which forms a part hereof. Like numerals refer to like parts in all 25 views of the drawing and throughout the description.

In the drawing:

Fig. 1 is an illustration of a face powder container in which the invention has been 30 embodied, the container being partly broken away to show the interior construction.

Fig. 2 is a cross section through the container lid, taken on the line 2—2, Fig. 3.

Fig. 3 is a plan view of the lower face of 35 the lid showing the invention in place.

Let the numeral 10 designate a face powder container and the numeral 11 the lid thereof. The container and the lid illustrated represent one of the types of containers at present on the market. The invention, however, is equally applicable to any type or shape of powder container and

the container per se forms no part of the present invention.

Secured to the under side of the lid 11 45 is a powder puff shelf 12 which is held in spaced relation to the lid by means of a connecting wall 13 which partially surrounds the shelf 12 and terminates in narrow peripheral flanges 14 which retain the 50 powder puff, shown at 16, on the shelf 12.

The free extremity of the shelf 12 is cut back, as shown at 17, to allow easy access for the removal of the powder puff.

Openings 15 may be formed in the shelf 55 12 to allow any accumulated powder to sift therethrough, in fact, the shelf could be formed almost entirely open, if desired, only sufficient stock being left to uphold the puff.

The uses and advantages of the improvement 60 are readily apparent and need no further description.

While a specific form of the improvement has been described and illustrated herein, it is desired to be understood that the same 65 may be varied, within the scope of the appended claim, without departing from the spirit of the invention.

Having thus described the invention, what I claim and desire to secure by Letters Patent is:—

Means for supporting a powder puff in a face powder container, comprising a shelf secured to the underside of the lid of said container, said shelf being partially surrounded by a wall by means of which it is secured and held in spaced relation to said lid and a peripheral flange on said shelf for holding said powder puff in place, said flange acting as a continuation of said wall 75 so that said puff may be passed over said flange into place on said shelf.

In testimony whereof, I affix my signature.

GERTRUDE B. DENNIS.
